BENZENESULFONAMIDO-HALO-PYRIMIDINES:
ANTIBACTERIALS

James L. Fedrick, Pearl River, and Gunnar S. Redin, New City, N.Y., and Robert G. Shepherd, Ridgewood, N.J., assignors to American Cyanamid Company, New York, N.Y., a corporation of Maine
No Drawing. Filed Feb. 20, 1961, Ser. No. 90,245
5 Claims. (Cl. 167—51.5)

This invention relates to new compositions of matter. More particularly, it relates to therapeutic compositions of substituted benzenesulfonamido-iodopyrimidines and a carrier.

In the development of sulfa drugs, sulfapyridine and sulfathiazole were found to be active but also somewhat toxic. Other sulfa drugs were developed which were more active, such as sulfadiazine and sulfamethazine. To avoid the requirement of dosage every four hours day and night, more slowly excreted sulfa drugs have been sought. The desirable feature of slow excretion of sulfa drugs is commonly called persistence of activity. The persistent or "long-acting" sulfa drugs most commonly used now are 3-sulfanilamido-6-methoxypyridazine and 4-sulfanilamido-2,6-dimethoxypyrimidine.

We have now found that high activity and persistence of said activity can be obtained by new compositions of matter comprising 2-sulfanilamido-5-iodopyrimidine, 2-(p-acetamidobenzenesulfonamido)-5-iodopyrimidine or 2-(p-nitrobenzenesulfonamido)-5-iodopyrimidine and a pharmaceutical carrier. The above compounds were described by Shepherd et al., J. Am. Chem. Soc. 70, 157-160 (1948). They are white crystalline solids of limited solubility in relatively non-polar solvents such as benzene, toluene, chloroform, ethylene chloride and the like; and somewhat more soluble in more polar solvents such as dimethylformamide, dimethylsulfoxide, lower alkyl alcohols, acetone, water, etc. These compounds are ordinarily purified by dissolving in aqueous alkali and neutralizing the resulting solution with aqueous acid.

It is unexpected that 2-sulfanilamido-5-iodopyrimidine would have high activity and persistence of said activity when closely related compounds such as, for example, 2-sulfanilamido-5-bromopyrimidine and 2-sulfanilamido-5-chloropyrimidine do not possess these properties. Single oral dosage in mice shows that the latter drugs are toxic to the extent of being about sixty times more toxic than the iodo derivative and, in addition, are less active and less persistent. The high activity of 2-(p-nitrobenzenesulfonamido)-5-iodopyrimidine and of 2-(p-acetamidobenzenesulfonamido)-5-iodopyrimidine is unexpected since it is well known [H. J. White et al., J. Pharmacol. 72, 112-122 (1941)], that such compounds are generally inactive. These substances, and in particular 2-sulfanilamido-5-iodopyrimidine, are so slowly excreted that they can be effectively used for prophylactic action using infrequent dosages such as one dose per week. The present compositions are unusual in also giving extremely good antibacterial activity both orally and subcutaneously.

The amount of single doses or daily doses to be given would vary with the size of the man or animal to be treated but should be such as to give a proportionate dosage of 1 to 500 mg./kg. per body weight. In terms of total weight of drug, this is usually from about 0.01 g. to 10.0 g. per dosage unit. In larger animals, obviously, larger dosage units may be desirable.

Experiments carried out using a single oral dose of various sulfa drugs 24 hours before infection with *Staphylococcus aureus* shows that 2-sulfanilamido-5-iodopyrimidine and 2-(p-nitrobenzenesulfonamido)-5-iodopyrimidine are greatly superior to the commonly used

2

sulfa drugs. The following Table I illustrates the results obtained.

TABLE I

5 *The Effect of Single Oral Doses Given 24 Hours Before Infection With Staphylococcus aureus, Strain Smith*

	Sulfa drug	Median effective doses, mg./kg.
10	Sulfadiazine	¹ Inactive
	3-sulfanilamido-6-methoxypyridazine	880
	4-sulfanilamido-2,6-dimethoxypyrimidine	¹ Inactive
	2-sulfanilamido-5-iodopyrimidine	320
	2-(p-nitrobenzene sulfonamido)-5-iodopyrimidine	290

15 ¹ Inactive at the highest dose (1,280 mg./kg.)

The present compositions containing 2-sulfanilamido-5-iodopyrimidine, 2-(p-acetamidobenzenesulfonamido)-5-iodopyrimidine and 2-(p-nitrobenzenesulfonamido)-5-iodopyrimidine are effective antibacterial agents against infection with *Staphylococcus aureus*, a commonly-used test organism and with many other organisms as shown hereinafter. The new compositions containing 2-(p-acetamidobenzenesulfonamido)-5-iodopyrimidine show the best activity when used in a prophylactic fashion, e.g. oral dosage six to twenty-four hours before infection.

TABLE II

30 *Prophylactic Treatment¹ of Staphylococcus aureus Infection*

35	Drug	Treatment		Relative antibacterial potency
		Single oral dose	Percent survival on 14th day	
	Sulfadiazine	320	100	1.0
40	Do	160	95	—
	Do	80	75	—
	Do	40	20	—
	Do	20	15	—
	2-(p-acetamidobenzenesulfonamido)-5-iodopyrimidine	320	100	0.3
	Do	160	50	—
	Do	80	10	—
45	Do	40	5	—
	Do	20	0	—

1 Treatment with the single oral doses shown six hours before infection of mice.

50 The compositions of the present invention containing 2-sulfanilamido-5-iodopyrimidine or 2-(p-nitrobenzenesulfonamido)-5-iodopyrimidine when tested against a number of infections where the standard infection is given to mice and the infected mice are treated by drug diet for seven days followed by a holding period of seven days, the following Table III illustrates the results obtained with the present compositions against various infections when compared to sulfadiazine.

TABLE III

60	Sulfa drug	<i>Streptococcus pyogenes</i>	<i>Diplococcus pneumoniae</i>	<i>Klebsiella pneumoniae, AD</i>	<i>Pasteurella multocida</i>	<i>Staphylococcus aureus, strain Smith</i>
65	Sulfadiazine	1.0	1.0	1.0	1.0	1.0
	2-sulfanilamido-5-iodopyrimidine	0.9	2.3	2.1	1.1	2.5
70	2-(p-nitrobenzenesulfonamido)-5-iodopyrimidine	0.6	1.0	1.2	0.7	1.0

70 Note.—Relative activities based on median effective doses against the various infections shown above. The standard infection given at 0 day; drug diet from -1 to +6 days; holding period 14 days after infection.

The unexpected high activity of the present compositions such as 2-sulfanilamido-5-iodopyrimidine when tested along with the commonly used sulfa drugs shows the great superiority of the present compositions over known sulfa drugs. These tests were conducted in mice and the infection used was *Streptococcus pyogenes* and *Staphylococcus aureus*. A summary of these tests is shown in the following Table IV.

TABLE IV
Percentage Survival of Infected Mice Treated With Various Sulfa Drugs

	Hour of dosing relative to infection	Treated with—					
		2-sulfanilamido-5-iodopyrimidine, percent	2-sulfanilamido-pyrimidine, percent	3,4-dimethyl-5-sulfanilamido isoxazole, percent	5-sulfanilamido-1-phenyl pyrazole, percent	2,6-dimethoxy-4-sulfanilamido pyrimidine, percent	3-sulfanilamido-6-methoxy pyridazine, percent
Group I-----	0	100	93	0	40	100	55
Group II-----	-24	100	37	0	10	30	0
Group III-----	-48	90	7	0	9	0	0
Group IV-----	-72	90	7				
Group V-----	-96	70	0				

In the above experiment the infection is *Streptococcus pyogenes*, beta hemolytic strain C203; 0.5 ml. of a 1:100,000 broth dilution of a 5 hour blood-broth culture was given intraperitoneally. The treatment: single subcutaneous dose of 500 mg./kg. contained in 0.5 ml. of 0.2% aqueous agar; at time of infection (0 hours) or before infection (e.g. "48 hours" signifies 48 hours before infection). Controls: 120 of 120 untreated infected mice were dead within 2 days after infection.

	Hour of dosing relative to infection	Treated with—					
		2-sulfanilamido-5-iodopyrimidine, percent	2-sulfanilamido-pyrimidine, percent	3,4-dimethyl-5-sulfanilamido isoxazole, percent	5-sulfanilamido-1-phenyl pyrazole, percent	2,6-dimethoxy-4-sulfanilamido pyrimidine, percent	3-sulfanilamido-6-methoxy pyridazine, percent
Group I-----	0	100	100	90	95	100	95
Group II-----	-24	100	100	0	30	85	20
Group III-----	-48	100	55	0	0	15	10
Group IV-----	-72	100	20	0	0	0	0
Group V-----	-96	95	10	0	0	0	0

In the above experiment the infection is *Staphylococcus aureus*, strain Smith: 0.5 ml. of a 1:100 broth dilution of a 5 hour blood-broth culture was given intraperitoneally. Treatment was a single subcutaneous dose of 500 mg./kg. contained in 0.5 ml of 0.2% aqueous agar at time of infection (0 hours) or before infection as indicated in hours (e.g. 24, etc.). Controls: 137 of 140 untreated infected mice were dead within 2 days after infection.

The sulfa drugs 2-sulfanilamido-5-iodopyrimidine, 2-(p-acetamidobenzenesulfonamido)-5-iodopyrimidine and 2-(p-nitrobenzenesulfonamido)-5-iodopyrimidine can be combined with a carrier and dispensed in any of the usual dosage unit forms of pharmaceutical preparations; for example, tablets, capsules, pills, suspension, as a powder or in any other desirable form in therapeutic quantities hereinbefore given. In the preparation of tablets, for example, the therapeutic agents may be combined with binders such as gum tragacanth, acacia, corn starch, gelatin etc. It is also usually desirable to have present a disintegrating agent such as, for example, corn starch, potato starch, alginic acid or the like. Also desirable usually is a lubricant such as stearic acid, magnesium stearate or talc along with sweetening agents such as saccharin. Flavoring agents may also be used such as peppermint, oil of wintergreen or cherry flavor. Larger tablets usually referred to as oblets of from 1-10 g. can be used in veterinary medicines. In the preparation of capsules, fillers such as enumerated above for tablets can also be used. The compositions when used in the form of suspensions or solutions may be combined with aqueous sugar or sorbitol type vehicle including a viscosity control agent such as Veegum (magnesium aluminum silicate), methocel or carboxymethylcellulose and a suitable preservative such as sodium benzoate or parabens (methyl and propyl p-hydroxybenzoic acid salts). In these liquid preparations, colorings, flavorings and buffers can also be included to produce a more pharmaceutically elegant preparation. It is also well-known in pharmaceutical practice to use a propylene glycol type

solvent for parenteral use with drugs having low aqueous solubility.

The new compositions of the present invention may be dispensed in dosage unit forms for a single daily therapeutic dose or in smaller units for multiple doses or in larger units for division into single doses. Parenteral compositions can also be dispensed in single units or in

larger quantities from which single doses are withdrawn at the time of use.

For use in veterinary medicine, the new compositions may be combined with edible carriers such as feed stuffs and so forth.

50 We claim:

1. A method of maintaining persistence of activity useful in the treatment of antibacterial infections which comprises administering in dosage unit form from 1 mg. to 500 mg./kg. of body weight of a sulfa drug selected from the group consisting of 2-sulfanilamido-5-iodopyrimidine, 2-(p-acetamidobenzenesulfonamido)-5-iodopyrimidine and 2-(p-nitrobenzenesulfonamido)-5-iodopyrimidine and an edible carrier.
2. A method of maintaining persistence of activity against bacterial infections which comprises introducing into the alimentary tract of animals having a bacterial infection, a therapeutic composition comprising from 1 mg. to 500 mg./kg. of body weight of 2-sulfanilamido-5-iodopyrimidine and an edible carrier.
3. A method of maintaining persistence of activity against bacterial infections which comprises parenterally administering into animals having a bacterial infection, a therapeutic composition comprising from 1 mg. to 500 mg./kg. of body weight of 2-sulfanilamido-5-iodopyrimidine and a parenteral vehicle.
4. A method of maintaining persistence of activity against bacterial infections which comprises parenterally administering into animals having a bacterial infection, a therapeutic composition comprising from 1 mg. to 500 mg./kg. of body weight of 2-sulfanilamido-5-iodopyrimidine and an edible carrier.

mg./kg. of body weight of 2-(p-acetamidobenzenesulfonamido)-5-iodopyrimidine and a parenteral vehicle.

5. A method of maintaining persistence of activity against bacterial infections which comprises parenterally administering into animals having a bacterial infection, a therapeutic composition comprising from 1 mg. to 500 mg./kg. of body weight of 2-(p-nitrobenzenesulfonamido)-5-iodopyrimidine and a parenteral vehicle.
